UNITED STATES PATENT OFFICE.

GRAY STAUNTON, OF MUSKEGON, MICHIGAN.

VALVE.

1,032,032.

Specification of Letters Patent.

Patented July 9, 1912.

Application filed November 6, 1911. Serial No. 658,842.

To all whom it may concern:

Be it known that I, GRAY STAUNTON, a citizen of the United States, residing at Muskegon, in the county of Muskegon and

5 State of Michigan, have invented certain new and useful Improvements in Valves, of which the following is a specification.

My invention relates to improvements in valves for hermetically sealed vessels, such 10 as fruit containing jars or the like.

One of the objects of my invention is to provide a valve that is automatically operable within itself to effect sealed closure of a vessel, from which air and gases have been 15 removed or exhausted.

In the drawing, Figure 1 is a central vertical section of a part of the vessel and a closure with my valve applied thereto; Fig. 2 is an enlarged detail of the valve and a 20 fragment of the closure.

In both views, the same reference characters indicate similar parts.

The valve herein described is an improvement on the valve shown and broadly 25 claimed in my Patent No. 934,102, dated September 14, 1909.

In the embodiment shown herein to exemplify the operation and use of my invention, 5 indicates the vessel having a large 30 open mouth and 6 is the closure therefor. A rubber band 7 is applied to an interior shoulder of the closure, by which sealing is effected between the closure and the mouth of the jar.

35 8 is the cylinder of an exhaust pump and 9 is the enlarged mouth thereof, provided with a yielding edge 10, which may be made of rubber, or other similar material, for making air-tight contact with the top surface 40 face of the closure, and for surrounding the valve 12, which is included within a perforation 11 made preferably in the center of the closure.

The valve is of a hollow cylindrical form, 45 provided with an interior arch partition 13, which joins the interior surfaces of the cylinder. The valve is preferably made of soft rubber and is pliable and compressible, so that the flange 14 may be inserted through 50 the perforation 11, in applying the valve to the closure.

15 is an upper flange which supports the valve in unsealed position, as shown in Fig. 1.

When air and gases are exhausted from 55 the vessel 5, as by means of the pump, the valve 12 is slightly lifted at each exhaust stroke of the pump and the confined air will escape from the vessel through the space between the exterior surface of the cylindrical 60 portion of the valve and the perforation 11 and the flange 15 will seat upon the upper surface of the closure upon the down-stroke of the pump piston. After the vessel has been thus exhausted, and the pump removed, 65 the difference of pressure existing in the interior of the vessel and the exterior thereof will cause the bridge part 13 to be depressed and straighten out, as shown in Fig. 2, until it occupies substantially a single horizontal plane, which effect uniformly increases the diameter of the valve around the entire circumference and causes the exterior sides thereof to make tight contact with the walls of the perforation 11, thereby completely filling the perforation with the valve 70 body and more thoroughly sealing the vessel against possibility of entrance of air. To break the seal, when it is desired to remove the closure 6, it is only necessary to 75 raise the flange 15 and further depress the part 13 by means of a smooth-end instrument, such as a match or the like, thereby contracting the cylindrical part of the valve and thus permitting air to enter the vessel 85 to release the top from the superposed pressure.

After the valve has been inserted in the closure, it remains permanently there unless purposely removed, and it is of such a character as to be easily cleaned and remains in a sanitary condition.

While I have herein described a single embodiment of my invention, it is obvious to persons skilled in the art that changes may 95 be made within the scope of the claims without departing from the spirit thereof.

What I claim is:

1. In a device of the class described, a vessel to be sealed, having a perforation, a 100 valve in said perforation, and means associated with the valve for automatically in-

creasing its diameter by the effect of the difference of pressure between the interior and the exterior of said vessel.

2. In combination with a vessel to be sealed, having a perforate wall, a hollow cylindrical valve, normally smaller than said perforation, and an expanding member for said valve adapted to increase the diameter of the valve by the effect of the difference of pressure within and without said vessel.

3. A pliable valve for a vessel to be sealed comprising a hollow cylinder, a projecting flange at each end thereof, and an interior arch-shaped wall closing said cylinder.

In testimony whereof I hereunto set my 15 hand in the presence of two witnesses.

GRAY STAUNTON.

In the presence of—

W. LINN ALLEN,
MARY F. ALLEN.
